UNITED STATES PATENT OFFICE.

VERNON L. TANNEHILL, OF FORT WAYNE, INDIANA, ASSIGNOR TO FORT WAYNE ENGINEERING & MFG. CO., OF FORT WAYNE, INDIANA.

AUTOMATIC PRESSURE-CONTROLLED SWITCH.

Application filed May 16, 1927. Serial No. 191,714.

This invention relates to automatic pressure controlled switches.

In pressure controlled switches, difficulty has been experienced in securing a proper range of adjustment and also in attaining an accurate control of the point or the pressure at which the switch will operate.

Objects of this invention are to avoid the difficulties noted above and to provide a switch controlled by pressure responsive means, which is so constructed that it has a wide range of adjustment and may be accurately set at the desired point with assurance that it will continuously function in a reliable manner.

Further objects are to provide a switch of the above type in which a sudden make and break is secured in a wholly automatic manner and by relatively simple mechanism, having a small number of parts.

Further objects are to provide a switch in which the parts are freely accessible so that they may be inspected or renewed as required and in which all of the parts are of rugged and sturdy formation.

An embodiment of the invention is shown in the accompanying drawings in which:

Figure 1 is a side elevation of the device with the cover in section;

Figure 2 is a sectional view approximately centrally of the device;

Figure 3 is a sectional view on the line 3—3 of Figure 1;

Figure 4 is a sectional view on the line 4—4 of Figure 1.

Referring to the drawings, it will be seen that the switch comprises a base portion 1 which is provided with a chamber 2 and with a screw threaded cap 3. Between the cap 3 of the base and the body portion 1, a diaphragm 4 is clamped. Preferably, gaskets 5 are provided, as shown in Figure 2, to provide cutting at the edges of the diaphragm. The chamber 2 communicates with a pipe 6 leading to the desired point. The cap 3 is provided with a cylindrical recess 7 within which the enlarged portion 8 of a plunger is slidably guided, said plunger continuing upwardly to provide a conical bearing portion 9.

The base is also provided with a pair of uprights 10 which are preferably integral with the cap portion 3 of the base and these uprights are joined at their upper ends to provide an overhanging flange or lip 11

apertured to receive the adjusting screw 12. The cap also carries a pair of bearing members 13 between which a lever 14 is pivotally mounted. This lever is recessed for the reception of the conical point 6 of the plunger and such recess is preferably located closely adjacent the pivot 15 of the lever. One end of the lever is connected to the tension spring or control spring 16, the other end of such spring being received in an aperture in the adjusting bolt or screw 12. The other end of the lever 14 is bifurcated and carries a grooved roller 17.

The uprights 10 have pivotally mounted between them a curved lever 18 which is provided with a downwardly extending arm 19 and with an outwardly extending portion. The outwardly extending portion carries a pivotally mounted or swingingly mounted link 20 whose lower end is provided with a cam portion 21. This cam portion 21, it is to be noted from Figure 2, is formed by two converging faces 22 and 23 which together form a peak. The link 20 is urged inwardly by means of the spring 24. The spring 24 is preferably anchored to the transverse portion 25 (see Figure 2) which joins upwardly extending arms 26 projecting from the members 13. An adjusting screw 27 is threaded through the overhanging upper portion 11 and limits the outward throw of the downwardly extending portion 19 of the lever 18.

The downwardly extending portion 19 of the lever carries a cross head 28 preferably formed of insulating material and held between a pair of lips integral with the lever. It is also desirable to secure the cross head in place by means of the screw 29, as shown in Figure 2. This cross head carries a pair of guiding channel-like clips 30 between which sets of spring fingers or movable contacts 31 are positioned. These spring fingers or movable contacts are urged inwardly by means of spring 32 loosely surrounding bolts 100 or screws 33 passing freely through the spring fingers and into the cross head.

The uprights 10 also carry insulating blocks 34, as may be seen from Figures 1 and 4. These insulating blocks in turn carry the stationary contacts 35 which are adapted to be joined by the movable contacts 31 when the parts are in the position shown in Figure 2.

It is to be noted from Figure 2, that the

roller 17 bears against the cam faces 23 or 22, depending upon the position of the parts. Preferably, the link 20 is thin at its lower end and fits within the groove of the roller. 5 As it is urged inwardly by the spring 24 its cam face produces an upward thrust when the parts are in the position shown in Figure 2, and consequently, the switch is in closed position and remains so, irrespective 10 of a certain limited motion of the lever 4. However, when the pressure rises above the desired point the roller passes the peak of the cam 21 and thus the thrust upon the link 20 is reversed and is now downward. 15 This is transmitted to the lever 18 and, consequently, quickly snaps the switch open.

Upon reverse motion of the lever 4, as for instance, when the pressure falls, the link 20 exerts a continuous downward pull until 20 the roller passes the peak of the cam 21 at which time an upward thrust is suddenly imparted to the link 20, thus closing the switch.

The device has a wide range of adjustment and the exact pressure desired may be secured by adjusting the nut of the bolt 12 (see Figure 2). Further, inasmuch as the link 20 is relatively long and the rocking motion due to its cam portion is limited, it 30 is apparent that a substantially uniform upward or downward pressure is exerted, due to the cam action in conjunction with the spring 24. Consequently, a very accurate control of the point at which the switch will 35 operate is secured by this construction.

It is to be noted also that although the switch has a quick make and break and is automatically controlled, that nevertheless it is of extremely simple and rugged construction and may be cheaply produced. In 40 addition to these features, the device is so made that all of the parts are readily accessible when the casing 36 is removed.

Although the invention has been described 45 in considerable detail, such description is intended as illustrative rather than limiting as the invention may be variously embodied and as the scope of such invention is to be determined as claimed.

50 I claim:

1. An automatic switch comprising a body portion having a chamber formed therein, a pipe leading from said chamber, a dia-

phragm mounted transversely of said chamber, a movable plunger operated from said diaphragm, a pivoted lever mounted above said plunger and contacting therewith, an adjustable spring urging said lever into engagement with said plunger, said lever having a grooved roller at its outer end, a pair of uprights carried by said body portion, a second lever pivotally mounted between said uprights, a link suspended from one end of said second lever and having a wedge-shaped cam portion fitting within the grooved portion of said roller, a spring urging said link inwardly towards said roller, said second lever having a downwardly extending arm, an insulating cross head carried by said arm, a movable spring contact fingers carried by said cross head, an insulating member carried by said uprights, and stationary contacts carried by said insulating member and adapted to cooperate with said spring 75 fingers.

2. An automatic switch comprising a body portion having a chamber formed therein, a pipe leading from said chamber, a dia- 80 phragm mounted transversely of said chamber, a movable plunger operated from said diaphragm, a pivoted lever mounted above said plunger and contacting therewith, an adjustable spring urging said lever into engagement with said plunger, said lever having a grooved roller at its outer end, a pair of uprights carried by said body portion, a second lever pivotally mounted between said uprights, a link suspended from one end of said second lever and having a wedge-shaped cam portion fitting within the grooved portion of said roller, a spring urging said link inwardly towards said roller, said second lever having a downwardly extending arm, an insulating cross head carried by said arm, a movable spring contact fingers carried by said cross head, an insulating member carried by said uprights, and stationary contacts carried by said insulating member and adapted to cooperate with said spring 90 fingers, said uprights having an adjusting screw adjacent their upper portions for limiting the opening movement of said switch.

In testimony that I claim the foregoing I have hereunto set my hand at Fort Wayne, in the county of Allen and State of Indiana.

VERNON L. TANNEHILL.
